BALL

John B. Dickson, Northampton, and Raphael A. Stafford and Paul E. Blanchfield, Chicopee, Mass., assignors to A. G. Spalding & Bros. Inc., Chicopee, Mass., a corporation of Delaware

Application August 3, 1940, Serial No. 350,378

8 Claims. (Cl. 273—60)

This invention relates to playballs, particularly baseballs, and to resilient materials useful in the manufacture of baseballs and other objects of controlled resiliency.

Present day baseballs have been evolved over a considerable period of time; and those used by the various baseball leagues, such as the American, National and International, are closely standardized for size and weight by definite and well-established rules. Moreover, great care has been exercised to provide a ball having suitable resistance to deformation, to provide sufficient softness in the ball to prevent injury to the hands in catching the ball, and to provide the other desirable qualities.

One standard baseball which has come into extensive use consists essentially of a leather cover superposed upon a center including woolen yarn winding, or divers yarn windings, about a main core consisting of an outer core concentrically enclosing a cork sphere or inner core $\frac{5}{8}$ of an inch in diameter, the hollow spherical rubber outer core being approximately $1\frac{1}{8}$ inches in diameter, or $4\frac{1}{8}$ inches in circumference.

In making the tests to determine the reactance to hitting of the different balls, a hitting machine driven by falling weights was used. This machine propelled a standard or "league" baseball a distance, after making allowances for such variables as wind velocity, of about 350 feet which is long enough to produce a home run in many ball parks. A large number of balls were tested against the standard distance of 350 feet. Until the development of the present invention, there have been no "short" balls, or those flying less than the standard distance for a standard blow, except certain balls having undesirable properties of lack of balance, tendency to be easily deformed, and other objectionable qualities.

Because of the development of the skill of baseball players, recent years have seen an objectionably large number of heavy hitters having the ability to hit a baseball so far as to assure a home run, or at least far enough to decrease the likelihood of a fly. The batting averages have been increased by this decreased likelihood of a hit being caught as a fly. The interest of some spectators in the game has lessened because of the increased number of home runs and the higher batting averages which have been attained.

To prevent an objectionably large number of home runs numerous attempts have been made to provide a satisfactory "short" or "dead" ball. These attempts have included the provision of:

looser or softer windings of yarn; thicker cords in the seams between the cover parts to absorb some of the blow from the bat; thicker cords in the seams between the cover parts to increase the wind resistance and to thereby cut down the flight; and special yarn windings on the centers.

While softer or looser windings of yarn did result in more sluggish baseballs, it was found that such balls were not practical because they were adversely deformed after being struck by a baseball bat a relatively few times. Thicker or coarser cords for the seams did not decrease the flight of the ball sufficiently to produce the desired result of making the game more interesting to the spectators by reducing the number of home runs and decreasing the batting averages of the players.

In the past it has not always been possible to place the main core at the true center of the ball in winding the yarn thereon, giving rise to erratic balls that could not be pitched uniformly by reason of being out of balance. Moreover, the large size of the winding on small diameter main cores may give rise to a greater tendency for the ball to be deformed.

At various times, particularly during the last few years, there has been considerable agitation for a "dead" ball. However, in many or most instances, the "dead" balls offered to the leagues by various manufacturers, when tried, proved to be just as long or in some instances even longer than the standard balls.

As used in this specification, the resiliency of a material refers to its tendency to move in counteraction to a force. For small forces, such as dropping an object from a height of 100 inches, or hitting it with a projectile moving at the rate of 23 feet per second, the term rebound is used. For large forces, such as dropping an object from a height of 625 feet or hitting it with a projectile moving at about 200 feet per second, the term reactance is used, as are the terms long and short. Durability refers to the property of resisting deformation or missshapeliness under continued whacking and not to oxidation resistance or the like. Heretofore, it has been thought that low resiliency of rubbery materials was necessarily accompanied by little durability.

It is an important object of the present invention to provide durable materials having low reactance and low rebound. A further object is to provide a baseball equivalent to former baseballs in substantially every respect except that

the number of home runs cannot be as high as in the use of the standard baseball.

Other objects of the present invention are:

To provide a method of controlling the sluggishness of durable resilient materials so that as the ability of baseball players improves, and as other conditions require it, material of suitably sluggish resiliency can be used.

To provide a baseball making use of a smaller quantity of costly wool yarn.

A feature of the present invention is the provision of durable resilient materials having low reactance and rebound.

Another important feature of the present invention is the provision of a large diameter main core, making possible the use of a relatively small yarn winding, thereby reducing the expense of manufacture of balls.

Other features include: the use of an air pressure main core for the baseball; the use of main cores of low rebound; and numerous other features apparent from a consideration of the specification.

In the drawings:

Figure 1 is a plan view of a complete baseball.

Fig. 2 is a sectional view taken on a line 2-2 of Fig. 1, showing the present preferred form of the present invention.

Fig. 3 is a sectional view taken similar to Fig. 2 but with a modified main core having a double rather than a single outer core on the main core.

Fig. 4 is a modification disclosing a compressed fiber inner core.

Fig. 5 is a cross-sectional view of the modified form of the invention with the main core having a hollow interior.

Fig. 6 is a modified form of the present invention with a solid one-piece or solid main core.

Fig. 7 is a chart showing the effect of changes in composition of shells upon the rebound of baseball main cores having 1½ inch diameters and enclosing 1 inch cores.

Fig. 8 is a graph showing the correlation of the rebound of baseball main cores and the reactance or shortness in flight of corresponding baseballs.

Fig. 9 is a graph showing the correlation of the size of the main core and the reactance or shortness of flight of corresponding baseballs.

Before describing the present improvements and mode of operation thereof in detail, it should be understood that the invention is not limited to the details of construction and arrangement of parts shown in the accompanying drawings, or to the details of the formulae herein described, which are merely illustrative of the present preferred embodiments, since the invention is capable of other embodiments, and the phraseology employed is for the purpose of description and not of limitation.

Referring now in detail to the drawings, Figs. 1 and 2 disclose a preferred form of the present invention wherein the novel structure comprises a conventional outer cover 10 which may be made of two pieces each cut out substantially in the shape of a figure 8 and laid edgewise to each other and secured one to the other by stitching in the well-known manner. Within the ball there is provided a main core A of particularly novel construction which will shortly be described in detail. Between the main core A and the cover is provided a yarn winding B which may be of any conventional and well-known form, preferably and in general comprising an outer

winding 11 formed from a close and tightly wound outer yarn or string substantially adjacent the outer cover 10, an inner winding 12, formed from a coarse yarn loosely or less closely wound directly over the main core A, and an intermediate winding 13 formed from a medium yarn or string between the inner and outer yarn winding 11 and 12.

The novel main core A shown in Fig. 2, provided by the present invention, should be particularly noted. Heretofore, main cores for baseballs have ordinarily been made of a hollow rubber sphere or outer core approximately 1½ inches in diameter enclosing a cork inner core and approximately 4½ inches in circumference. Such a main core rebounds approximately 45 to 50 inches when dropped 100 inches onto a hard surface, or in other words has a rebound of 45% to 50%. The main core A provided by the present invention differs from the conventional ones in many respects. Of importance it is constructed so that it has a rebound at least 40% less than that of the conventional main core, and some have been already made with a rebound of 11 inches, or 78% less than the standard of 50 inches for conventional ones. The reduction in rebound is accomplished by the use of blends of synthetic rubbers such as Vistanex, Thiokol, A. X. F. and Koroseal. In order to achieve the desired resiliency it is ordinarily preferable to use smoked rubber sheets in the composition. The use of curing agents, plasticizers, accelerators, fillers, etc., is according to the usual practices in such compositions. Because such fillers as felt affect the resilience of rubber, the percentages used in describing the formulae are given with the entire composition as 100% instead of including only the rubbery materials as the basis for 100%. By way of example, the following formulae illustrate the making of synthetic rubber mixtures of limited resiliency:

Formula A

Formula A includes a mixture of 30 parts smoked sheet, 70 parts A. X. F., together with suitable curing agents, such as: gas black 5 parts, sulfur 10 parts, D. P. G. 3 parts, Tuads 1 part, and stearic acid 5 parts, and if desired, not more than 25 parts of loose fiber such as felt scrap and/or not more than 10 parts of zinc oxide or other mineral filler.

The hemispherical shells used in making the outer core of Formula A are preferably given a semicure at 30° F. for 5 minutes and the core itself is given a final cure at 311° F. Alternatively, the hemispherical shells may be given a semicure for 7 minutes at 280-287° F. and the main core may be given a final cure for 30 minutes at 280-287° F. Expressed in percentages, Formula A comprises 18-22% rubber and 44-52% A. X. F.

A. X. F. is a rubber soluble, resilient, somewhat plastic polyxylene material prepared by the catalytic condensation of ethyl chloride and benzene, as described by Shinkle, Brooks and Cody in "Industrial and Engineering Chemistry," vol. 28, 275, 1936.

Main cores A outer cores or shells 15 made of Formula A material comprising 18% rubber and 44% A. X. F. and considerable felt scrap, with an outside diameter of 1½ inches, and having a cork inner core 14 which is ½ inch in diameter, had a rebound of 20-30 inches when dropped 100 inches upon a hard object at 21° C., or a rebound 40-60% less than conventional main

cores. Balls made with these main cores average about 10 feet less in flight than standard baseballs, thereby shortening the flight about the desired amount for the present skill of many ball players.

If, in making Formula A material, 12 parts of felt are used instead of 25 parts of felt, the rebound is reduced to 17 inches. If no felt is used, the rebound is reduced to 11 to 12 inches. As shown in the graph of Fig. 8, the general rule is that the shortness of the baseball, or the reduction in the flight of the ball, is dependent upon the rebound of the main core. The correlation is not perfect, but provides a convenient standard of reference.

Each of the three above-described main cores weighed approximately 1.31 to 1.38 oz.

In developing the present invention it was found by making many tests that when a rubber outer core of a conventional main core is increased in size, the flight of the corresponding baseball is increased. Even if a wool main core is substituted for a rubber main core, a long ball results. It is by the use of a medium size rubbery main core or rubbery covered main core in combination with a medium size yarn winding that a baseball having only the standard distance of flight has been produced. According to the present invention, the size of a low rebound main core, such as one made of Formula A, is increased beyond the usual size, suitably to 1½ inches. It was found that the flight of the corresponding baseball was materially shortened. It was found that increasing the size of the low rebound main core from 1⅓, the conventional size, to 1½ inches did not produce a great change, but that when the diameter was increased to 1½ inches the flight was considerably shortened, and that additional increases of diameter, at least up to 2 inches, further decreased the flight of the ball, as shown by the graph of Fig. 9. Just what causes this falling off within those rather close limits is not exactly known.

By increasing the diameter of the main core relative to the outside diameter of the ball, which according to this invention need not be changed, the thickness of yarn winding B may be substantially decreased and the possibility of deformation of the completed ball may be reduced. Also, thereby, considerable economy is effected by using a smaller quantity of usually expensive wool yarn.

From the foregoing it will be apparent that contrary to what might be expected, a shorter rather than longer flight is achieved when the main core of the present invention is brought closer to the outer cover. Also, a more uniform ball is obtained since it is possible to closely weigh and control the amount of material being built into the main core. Yarn is normally somewhat nonuniform in size and of uneven weight. When several hundred yards of yarn are wound upon each of a number of balls, there is considerable likelihood that the finished balls will have adverse differences in weight even though the length of the yarn is very closely controlled. Therefore, the use of a smaller quantity of yarn according to the present invention makes possible a more convenient and more accurate control of the weight of the ball.

Heretofore there has been only a relatively small amount of empirical data regarding the factors influencing the distance of flight of a baseball. By extensive research and testing, it

has been found that several factors influence the distance flown by a baseball when hit by a force approximately equivalent to that involved in a home run hit. Disregarding the wind, air resistance, etc., it can be said that the flight is dependent upon: (1) the forcefulness of the restoring forces of the resilient materials comprising the ball, (2) the speed of the restoring forces of each component, (3) the quantity of each component, (4) the relative location of each component, and (5) the capacity of the materials used to restore themselves to their original shapes.

The results of more than fifty tests are taught by the graphical presentation of a great amount of laboratory data in Figs. 7, 8 and 9. The numbers for the points on the graphs refer to index numbers for laboratory data. Fig. 7 shows the effect of changes in composition of the outer core upon the rebound of 1⅓ main cores containing 1 inch cork inner cores. The left-hand section of the chart shows the inches of rebound of the main cores, and the right-hand section shows the composition of the durable outer cores as given by the percentages of the rubbery components. The lower portions of both sections relate to Formula A material, and demonstrate that as the percentage of A. X. F. is increased, the rebound is decreased. Similarly, the upper portion of Fig. 7 shows that as the percentage of Vixtanex is increased, the rebound is decreased, and also that as the percentage of modifying material consisting of a mixture of Vixtanex and Thiokol is increased, the rebound is decreased.

Fig. 8 illustrates the correlation between the rebound of the main core and the shortening in flight of the corresponding baseball showing that as the rebound is decreased, the flight is shortened. The bottom horizontal scale indicates the rebound in inches, and the left-hand vertical scale relates to the shortening of the flight in feet.

Fig. 9 shows the correlation between the diameter of the main core and the shortness of flight of the corresponding baseball when a low rebound material is used for the outer core. The bottom horizontal scale shows the shortening of flight in feet, and the left-hand vertical scale marks the diameter of the main core. Inner cores of cork, and outer cores of Formula A material having a rebound of about 19 inches, were used in the tests shown in Fig. 9.

When the skill of baseball players justifies it, a baseball having a shortening in flight considerably greater than 30 feet can be produced by the use of a very large main core of very low rebound. At the present time the skill of the players requires a ball about 10 feet short in flight. If a slightly greater shortening were desired, reference could be made to Figs. 7, 8 and 9 for the formulation of such a ball. For example, a ball having an outer core containing 51% Vixtanex and 11% rubber, and being 1⅓ inches in diameter, and enclosing a 1 inch cork core to form a main core having a rebound of 16 inches, would be 13 feet short. An example of a formula for such an outer core would be:

Formula B

Formula B includes a mixture of 30 parts smoked sheet, 140 parts Vixtanex, and suitable fillers and curing agents such as 25 parts felt scrap, 20 parts zinc oxide, 5 parts gas black, 10 75 parts sulfur, 3 parts D. P. G., 1 part Tuads, and

1 part stearic acid. Vistanex is a rubber soluble, resilient, synthetic macromolecular material obtained by polymerizing refinery gases containing essentially isobutylene.

That modification shown in Fig. 3 comprises a ball very similar to that shown and described in connection with Figs. 1 and 2, differing from the latter primarily in the provision of a main core C after the teaching of Reach Reissue Patent 17,200. A cork inner core 16 is enclosed within an intermediate core 17 which is enclosed within an outer core 18 of cured and vulcanized rubber. The intermediate core 17 is preferably made of Koroseal, a rubber soluble, resilient, synthetic macromolecular material obtained by polymerizing vinylchloride. The manufacture of Koroseal, A. X. F., Vistanex, Thiokol, and other rubber soluble resilient synthetic macromolecular materials is described by D. North in the April 1940 issue of "Chemical and Metallurgical Engineering," vol. 47, 22.

According to the present invention, the resiliency of a playball is controlled not only by means of the size and composition of the outer core but also by the size and composition of the inner core. That modification shown in Fig. 4 comprises a main core D and includes an inner core 19 which is made of compacted kapok. It has been found that cork inner cores have a rebound of about 26 inches and that kapok inner cores have a rebound of 19 inches. The outer core 20 of Fig. 4 may be made of Formula B material. To provide a ball having an even shorter flight, the inner core may be made of Vistanex. Using a 1 inch Vistanex inner core and 1½ inch shells made of a material comprising 14% rubber, 21% Vistanex, 36% Thiokol, 17% felt scrap, and suitable curing agents, a ball was obtained having satisfactory durability, and having a flight 35 feet less than the standard ball. Thiokol is a polyalkenesulfide.

The form of the invention disclosed in Fig. 5 differs from the forms previously described primarily in the provision of a main core 21 in the form of a hollow sphere filled with gas or air at a pressure of approximately 25 pounds. Preferably the main core 21 is approximately 1½ inches in diameter with a hollow interior approximately 1½ inches in diameter. Satisfactory results can be obtained by making the main core 21 of a composition such as Formula A or Formula B, especially if fillers and curing agents are used so as to produce an air pressure main core having considerable stiffness and little compressibility. If the main core 21 has too much compressibility, an impact will shift the windings to produce a misshapen ball. It was found that the ball made with said air pressure main core was 30 feet short of the standard controls.

In making a baseball consideration must not only be given to size and resiliency but also to the weight of the ball members. Many materials otherwise satisfactory cannot be used because of their specific gravity. To obtain a ball of proper weight it has been customary to use an inner core of cork or similar material, and attempts to avoid it have ordinarily been unsatisfactory by reason of the lack of durability of the ball or the increase in its flight. That form of the invention disclosed in Fig. 6 provides a solid main core 22 which is made of like material throughout its entire mass, and it does not include a separate inner core on the inside of a hollow rubbery sphere. This solid main core 22, so that it will

not be excessive in weight, is preferably made according to one of the following formulae:

Formula C

Formula C includes as its main constituents: 10 parts smoked sheet rubber, 80 parts Vistanex, 200 parts Thiokol, and 100 parts ground cork and suitable curing agents such as 6 parts D. P. G., 3 parts Tuads, 15 parts zinc oxide, 12 parts gas black, 6 parts stearic acid, and 9 parts sulfur. Expressed in percentages, Formula C comprises 4% rubber, 18% Vistanex, 45% Thiokol, and 23% cork. This composition had a rebound of 11 inches.

Formula D

Formula D is a cork mixture using 30 parts smoke sheet, 70 parts A. X. F., 60 parts ground cork, and suitable curing agents such as 5 parts sulfur, 5 parts gas black, 5 parts zinc oxide, 3 parts D. P. G., 1 part Tuads, and 1 part stearic acid. A baseball using a solid main core of this composition was 13 feet short of the standard.

If the solid main core were made of ordinary rubber, the baseball would be long instead of short; moreover, there is likelihood that it would change shape considerably, as has been found in actual tests. Making baseballs with solid rubber main cores lengthened flight and decreased durability. However, by making this solid sphere of the materials aforementioned the flight is shortened and the durability is increased.

The selected materials, forming in the finished ball an intimate elastic mixture, are suitably compounded in the usual manner and with ingredients commonly used for the purpose of curing, filling, pigmenting and the like. The materials or admixtures may be blended, shaped, and cured with conventional machinery. All proportions used in the specification and claims refer to parts or percentages by weight.

Variations and modifications may be made within the scope of this invention, and portions of the improvements may be used without others.

Having thus described the invention, what is claimed as new is:

1. In a durable sluggish baseball the combination of a main core, a major portion of the mass of which is made from a mixture comprising at least 10% modifying material chosen from the class consisting of polyisobutylene, polyalkenesulfide, polyxylene, polyvinylchloride and similar synthetic rubber and resinlike materials, said main core being approximately 1½ to 2 inches in diameter, said main core having a rebound of less than 30 inches when dropped 100 inches; an outer cover approximately 9 to 9½ inches in circumference; and at least one yarn winding between the center and the outer cover.

2. In a durable sluggish baseball the combination of an inner core having a diameter of from ¾ of an inch to 1½ inches approximately; a hollow spherical member surrounding said inner core, said hollow spherical member having an outside diameter of approximately 1½ to 2 inches, said hollow spherical shell being made of a composition including at least 25% modifying material chosen from the class consisting of polyisobutylene, polyalkenesulfide, polyxylene, polyvinylchloride, and similar rubber soluble, resilient, synthetic macromolecular material; said hollow spherical member combining with said inner core to constitute a main core having a rebound lower than thirty inches in a 100 inch

drop; an outer cover; and at least one yarn winding between the main core and the cover.

3. In a baseball the combination of an inner core of compressed kapok; a rubbery outer core including at least 25% modifying material chosen from the class consisting of polyisobutylene, polyalkenesulfide, polyxylene, polyvinylchloride, and similar rubber soluble resilient, synthetic macromolecular material; an outer cover; and at least one yarn winding between the cover and the outer core.

4. In a baseball an inner core of polyisobutylene, said core being of a relatively large diameter.

5. A durable sluggish baseball including relatively large core members with respect to core members of conventional league baseballs, said core members including at least 25% modifying materials chosen from the class consisting of polyisobutylene, polyalkenesulfide, polyvinylchloride and polyxylene, and said core members having a rebound of less than 30 inches when dropped 100 inches.

6. A playball including a relatively large inner core of polyisobutylene and an outer core member of rubber and at least 25% modifying materials chosen from the class consisting of polyisobutylene, polyalkenesulfide, polyvinylchloride and polyxylene.

7. In a curable sluggish baseball, the combination of a nonfibrous, rubberlike main core, a major portion of the mass of which is made from a mixture comprising at least 10% modifying ma-

terial chosen from the class consisting of polyisobutylene, polyalkenesulfide, polyxylene, polyvinylchloride and similar synthetic rubber and resinlike materials, said main core being approximately 1½ to 2 inches in diameter, and having a rebound of less than 30 inches when dropped 100 inches; an outer cover approximately 9 to 9¼ inches in circumference; and only tightly wound windings of textile filaments between the main core and cover.

8. In a durable sluggish baseball, the combination of a nonfibrous inner core having a diameter of approximately ¾ to 1⅓ inches; a nonfibrous, rubberlike hollow spherical member surrounding said inner core, said hollow spherical member having an outside diameter of approximately 1½ to 2 inches, and having a composition including at least 25% modifying material chosen from the class consisting of polyisobutylene, polyalkenesulfide, polyxylene, polyvinylchloride, and similar rubber soluble, resilient, synthetic macromolecular material, and said hollow spherical member combining with said inner core to constitute a main core having a rebound lower than 30 inches in a 100-inch drop; an outer cover 9 to 9¼ inches in circumference; and only tightly wound windings of textile filament between the main core and the cover.
